UNITED STATES PATENT OFFICE.

DANIEL J. CHICKERING, OF SPOKANE, WASHINGTON, ASSIGNOR OF FIFTY-ONE PER CENT TO EGGERS POLE & SUPPLY COMPANY, OF PARKWATER, WASHINGTON.

PORTABLE PUNCHING MACHINE.

Application filed April 2, 1925. Serial No. 20,146.

To all whom it may concern:

Be it known that I, DANIEL J. CHICKERING, a citizen of the United States, residing at Spokane, in Spokane County and State 5 of Washington, have invented certain new and useful Improvements in Portable Punching Machines, of which the following is a specification.

My present invention relates to improvements in portable punching machines especially adapted for the purpose of punching holes in the surface of logs or poles, as telephone or telegraph poles preparatory to impregnating the wood of the pole with a preservative, such as carbolineum, which is applied as by dipping the punched pole into a vat or container for the preservative.

The machine is motor operated and manually controlled and manipulated and 20 utilizes a gang of reciprocating tools for punching the surface of the pole. The machine is self-contained and its operating parts which are few in number are compactly arranged for speed in their movements and for quickly and satisfactorily puncturing or punching the pole.

In use the machine is placed upon the top of a horizontally disposed and properly supported pole or other object to be punched, 30 and the machine, by manual power is shifted longitudinally of the pole, preferably step by step, from one end of the area to be punctured or punched to the other end and then returned. As the machine is moved 35 forward and back the pole is turned on its longitudinal axis while the machine is maintained in upright position in order that the entire area to be punched may be filled with holes in desired number. A gang of punches 40 are actuated by power from a motor as the machine is manipulated, said punches being mechanically lifted against the tension of springs, and by these springs forced downwardly to penetrate the wood on their working strokes.

In the accompanying drawings I have illustrated one complete example of the physical embodiment of my invention wherein the parts are combined and arranged for the 50 practical application of the principles of my invention.

Figure 1 is a view in side elevation of a machine embodying my invention.

Figure 2 is a top plan view of the machine of Figure 1.

Figure 3 is an enlarged detail elevation partly in transverse section showing the punch or tool frame and the gang of punches.

Figure 4 is an enlarged vertical sectional view showing the cam actuating means for a punch.

The machine is mounted upon a main frame or carriage 1 of generally rectangular shape, and with its parts compactly arranged for supporting the operating parts of the mechanism. The transversely disposed axles 2 and 3 are provided for the carriage and provided with concave rollers 4 and 5 shaped to conform to the exterior 65 surface of the pole P over which the rollers are designated to travel longitudinally of the pole. The machine is designed to be propelled manually along the pole backward and forward over the area to be punched, 70 preferably with a step by step movement, or an intermittent movement regulated according to the movement of the gang of punches.

Power for the operating mechanism carried by the main frame or carriage is supplied from an electric motor 6 which is located at what may be termed the front end 80 of the machine and by its weight adds to the stability of the machine.

The punching mechanism comprises two 85 alternating sets of tools which are mechanically lifted or elevated and caused to move on their downward strokes by spring pressure applied thereto. For elevating the tools or punches a cam mechanism is employed and operated from the motor 6 through a small pinion 7 on the motor shaft 8. A larger gear wheel 9 with its shaft 10 journaled in the main frame and also in a housing 11 at the side of the main frame 90 receives power from the pinion, and the shaft 10 has thereon a smaller gear 12 which meshes with a driven gear wheel 13 on the cam shaft 14. The cam shaft is journaled in the main frame and extends transversely 95 of the carriage or frame in position between the front and rear rollers of the carriage.

Upon the cam shaft are keyed a series of cams or cam disks 15 having spacing collars 16 between adjoining cams and these cams 100 or cam disks are arranged in two sets to

alternately lift their respective sets of spring pressed punching tools through the instrumentality of a series of levers also operating in two sets.

- 5 These lifting levers 17 are of identical construction and are pivoted on the lever bar 18 arranged parallel with the cam shaft and supported in the upper part of the main frame or carriage back of the cam shaft.
- 10 Each lever has a lug 19 on its under edge to ride upon the peripheral edge of one of the cam disks, as seen in Figure 4, and at its free end the lever has a lifting lug 20 for co-action with the punching tool.
- 15 The punching tools are arranged in a series extending transversely of the machine and reciprocating in two alternate sets. As seen in Figures 3 and 4 the tool preferably has a shank 21 square in cross section and a 20 laterally projecting head 22, the latter for co-action with the lifting lug 20 on the free end of the cam lever. At its lower end the shank has a socket 23 for a pointed punching tool 24 which is detachably secured in 25 the socket by suitable means.

The punching tools are carried in the tool frame 25 located transversely of the main frame and supported as by bolts therein. As seen in Figures 3 and 4 the 30 punch frame or tool frame is provided with a plurality of sockets 26 which are arranged on angular lines which converge toward the longitudinal axis of the pole P in Figure 3 and the two sets of punches are located 35 in these sockets and adapted to reciprocate therein. In the upper ends of the sockets are located tension springs 27 which are compressed and interposed between the top ends of the shanks 21 and screw plugs or 40 closures 28 for the sockets, and it will be apparent that the springs are designed to urge or force the respective tools downwardly on their working strokes toward the pole.

45 Handles 30 are attached at the respective ends of the carriage or main frame for use by two attendants who may utilize these handles for manipulating the machine and propelling it forward and backward on the pole P in time with the power operated 50 punching tools. The tension of the springs 27 may be varied and the pressure of the tools also varied to adjust the power of the punches by turning the screw plug 28 in the top ends of the sockets. The lower end of 55 the tool shank projects below the tool frame and the punch as a whole is capable of a vertical sliding or reciprocating motion in its sockets. Each set of punches is alternately lifted against the tension of the respective springs 27 through the co-action of the rotating cams and levers. As the cam and lever lift the tool as indicated in dotted lines in Figure 4 the spring is compressed, 60 and as the shoulder 16 of the cam reaches

the position of Figure 4 the lifting movement ceases and the spring is released. The spring immediately expands, forcing the punching tool downwardly on its working stroke to punch the pole P. The free end 70 of the lever falls, as soon as it is freed, to the full position in Figure 4.

From this description taken in connection with my drawings it will be apparent that I have provided a portable machine which 75 is manually propelled for forward and reverse movement on the pole. The operation of the two sets of tools is accomplished in unison and on alternating strokes to reduce 80 undue vibration of the machine and this alternate movement may readily be provided for by adjusting the two sets of the cams with relation to one another. After the carriage has traveled the required distance in one direction on the pole it is stopped and then 85 propelled in the reverse direction with the tools in operation. The pole or other work being punched is turned at the proper intervals in suitable manner, and the work progresses until the desired result is accomplished. 90

Having thus fully described my invention what I claim as new and desire to secure by Letters Patent is—

1. The combination in a portable punching machine with a carriage, of a punch frame supported in the carriage and a series of reciprocable punches in said frame, an operating shaft and a motor on the frame, power transmission mechanism between said 100 motor and shaft for lifting said punches, and means for automatically operating said punches on their downward working stroke. 95

2. The combination in a portable punching machine with a carriage, of a punch frame supported in the carriage, a gang of reciprocable punches supported in said frame and arranged in sets to move in opposite directions, an operating shaft and a 105 motor and driving connections between said motor and shaft, means actuated by the shaft for positively lifting one set of tools and automatic means for causing a downward working stroke of the other set of tools while the other set is being lifted. 110

3. The combination with a carriage of a punch frame having a series of sockets, a gang of punches in said sockets, a motor, an operating shaft and driving connections between said motor and shaft, means actuated from said shaft for lifting said gang in alternating sets, and resilient means for causing a downward working stroke of said punches. 115

4. In a punching machine the combination with a carriage having handles for manual manipulation and propulsion and a pair of spaced traction rollers, of an operating shaft, a motor and driving connections between said motor and shaft, a gang of 120 punches. 125

reciprocable punching tools, means actuated from said shaft for lifting said tools, and resilient means for causing a downward working stroke of said tools.

5 5. In a punching machine the combination with a carriage having a pair of spaced traction rollers of a cam shaft, a motor and driving connections between said motor and shaft, a series of cams on said shaft, a sup-

porting bar and a series of cam levers pivoted thereon for coaction with the cams, a gang of reciprocable punches and connections between said levers and punches for elevating the latter, and springs for causing a downward working stroke of said punches. 10 15

In testimony whereof I affix my signature.

DANIEL J. CHICKERING.
